Filed Jan. 3, 1960, Ser. No. 63,425

Term of patent 14 years

(Cl. D80—10)

FIG. 1.

FIGURE 1 is a perspective view of a merchandise display stand embodying my new design, the center of the lower four shelves being broken away for convenience of illustration;

I claim:

The ornamental design for a merchandising display stand, as shown and described.
